UNITED STATES PATENT OFFICE

HARRY B. MEIBERS, OF SPRINGFIELD, OHIO

PUZZLE

Application filed November 18, 1929. Serial No. 408,062.

This invention appertains to new and useful improvements in games and more particularly to a game of the card type.

The principal object of this invention is to provide a game of cards, wherein the cards are to be arranged in such a manner as to spell words and to form a combination of numerals consistent with instructions.

In the following specification and claim, important objects and advantages of the invention will become apparent to the reader.

In the drawings:

Figure 1 represents a view of the cards in properly assembled order, showing the letters arranged to form predetermined words, and the words in turn, being made up of particular letters so as to constitute the proper number combination.

Figure 2 represents an end elevation of the assembly shown in Figure 1.

Figure 3 represents a chart showing the words to be spelled with the cards.

Figure 4 represents a perspective view of one of the cards.

Figure 5 represents a chart that may be published in newspapers.

Figure 6 represents a chart that may be printed in newspapers and cut out, the same showing the combinations of numbers that may be pasted to the letter squares shown in Figure 5, after the squares have been cut from the newspaper.

Referring to the drawings, wherein like numerals designate like parts, it will be seen that the game is played with cards such as are shown in Figure 4 and denoted by numeral 5. In one corner of each card a combination of two numbers is placed and this is denoted by numeral 6. On the same side of the card, a letter is placed and this is denoted by numeral 7.

With each game, a list of the combinations is afforded in the form of a chart. The numeral combinations on this chart may be varied if desired without departing from the spirit of this invention. However, in order to properly guide the player, the combinations must be so pre-arranged as to allow for a key numeral, which in the present instance is the numeral 8.

When the letters have been properly arranged and the numerals so arranged as to constitute the required combination for each word, the key number should appear at a predetermined position in each word. 55

The instructions for playing the game are as follows:

Place the eleven key number combination cards in designated vertical columns for convenience the remaining fifty-five cards being 60 separated alphabetically so as to permit the selection of the next card desired to be more convenient. It is not necessary to spell the words in the order listed on the chart, in fact, only extreme skill would enable the 65 players to solve the puzzle in that manner.

The puzzle can be solved systematically, and discovering the proper method to use is one of the interesting features to be found in operating the same. The existence of the 70 key number should always be borne in mind in playing the game so that the key numbers should be in the column of letters designated in the instructions.

In the drawings the key number is 8 and is 75 located in the fourth column of letters of the assembled game. (See Figure 1.) In conjunction with this requisite, each horizontal row must be made up of letters whereon the combination of numerals in aggregate extend from one to twelve consecutive 80 lines, with no omissions or duplicates.

In Figures 5 and 6, the chart 11 is printed in the newspaper, and the indicia consists 85 of vertical and horizontal lines 12 and 13 respectively for dividing the chart into a definite number of blocks, and in each block a letter 14 is located. These blocks are to be cut from the chart. 90

In Figure 6, numeral 15 represents a second chart that is to be printed in the newspaper for use in connection with the chart 11. This chart is divided horizontally by lines 16 and vertically by pairs of closely spaced lines 17. Within the blocks defined by the horizontal lines 16 and the pairs of lines 17, the combination numerals 18 are to be placed, while the letters 19 are located within the spaces of each pair of vertical 95 lines 17. 100

The numeral combinations are cut out and pasted on the letter blocks shown in Figure 5 and the game is to be played in the same manner as hereinbefore set forth.

5 While the foregoing description sets forth the invention in definite terms, it is to be understood that changes in the manner of playing the game by re-arranging the combinations and letters and certain other various 10 features may be made without departing from the spirit and scope of the claim here-to appended.

Having thus described the invention, what is claimed as new is:

15 A set of cards adapted to be assembled in edge abutting engagement in transverse and longitudinal rows, each card bearing a single letter of the alphabet, the letters being so chosen as to spell a word in each transverse 20 row when the cards are arranged in certain sequence, each of the cards being further provided with two different numerals, said numerals being so chosen that all of the numerals within a given range will appear 25 in each transverse row of the cards when said cards are arranged in the aforementioned certain sequence, the numerals further being so chosen that one of said numerals will be common to all of the cards in one of 30 the vertical rows to provide a key card for each transverse row.

In testimony whereof I affix my signature.
HARRY B. MEIBERS.
